UNITED STATES PATENT OFFICE

ARTHUR A. BRADLEY, OF HARTFORD, CONNECTICUT, ASSIGNOR TO UNDERWOOD ELIOTT FISHER COMPANY, OF NEW YORK, N. Y., A CORPORATION OF DELAWARE

WORK PACK

Application filed November 10, 1925. Serial No. 68,059.

This invention relates to machines for facilitating the handling of work-sheets in typewriting machines, and is especially adapted to be used in certain systems of book-
5 keeping.

Bookkeeping machines are usually provided with a tally mechanism having a supply spool around which is wound a strip of carbon together with a strip of paper. Said
10 tally-strip is passed under the platen and is rewound onto a receiving spool which is connected to the line-spacing mechanism of the machine. The center feed-rolls are usually removed and the tally-strip is made narrower
15 than the width between the outer feed-rolls, so that in case the platen is rotated by the finger-piece at the end thereof, the tally-strip will remain stationary. In connection with said tally-strip it has been customary to in-
20 sert a statement-sheet in front of the tally-strip, said statement-sheet being wide enough to engage the feed-rolls, thereby rendering it feasible to feed the statement-sheet independently of the tally-strip.

25 Sometimes, however, this is objectionable, and instead it is desirable to use a statement-sheet no wider than the tally-strip. In this invention a work-sheet combines a statement-sheet and a record-sheet, held together by a
30 weakened line at the top thereof. The statement-sheet may be as wide as the tally-strip, and the record-sheet much wider, being wide enough to engage the feed-rolls of the machine.

35 The two sheets are interleaved with a sheet of carbon so as to form a pack which is inserted at the rear of the platen so that the borders of the statement-sheet coincides with the edges of the tally-strip. The platen is
40 then rotated and the assembled pack is positioned to receive the first line of typing, whereupon the work-sheet is line-spaced by means of the line-spacing mechanism, which also line-spaces the tally-strip. Owing to the
45 construction of the machine it is possible to simultaneously line-space both the work-sheet and the tally-strip by means of the line-space handle, and at the same time to position the work-sheet without disturbing the tally-
50 strip.

Other features and advantages will herein-after appear.

In the accompanying drawings,

Figure 1 is a front view of the invention as applied to an Underwood standard type-
writing machine. 55

Figure 2 is an end view, showing the tally- mechanism connected to the line-spacing mechanism of the machine.

Figure 3 is a cross-section through the center of the machine. 60

Figure 4 is a perspective view of the work-sheet.

This invention is illustrated as applied to an Underwood standard typewriting machine, 65 which has, as regular equipment, a platen 10, journaled in the end plates 11 of a platen-frame, upon which there is secured a tally- mechanism. Said machine is also provided with a line-spacing mechanism or sliding 70 member 12, and typing instrumentalities represented by a type-bar 13.

The tally-mechanism includes a supply- spool 14, around which there is wound a tally- strip 15 and a strip of carbon 16. The strips 75 are inserted at the introductory side of the platen, under and around the same, past the printing point, and are rewound onto a receiving spool 17 which is connected to the line-spacing mechanism 12. When the ma-
chine has a tally-mechanism, it is customary 80 to remove the center feed-rolls, and only the outer rolls 18 are left on the feed-roll-shaft 19, so that the tally-strip may be fed around the platen independently of the feed-rolls. To 85 this end, there is provided mechanism for operatively connecting the receiving spool 17 to the line-spacing mechanism. Said mech-
anism may include a pair of spur-gears 20 and 21, respectively secured to the spool 17 90 and to a shaft 22, which has also secured there-
to, at the end thereof, a ratchet 23 co-operat-
ing with a pawl 24 fulcrumed on an arm 25
which is pivotally mounted upon said shaft 22. The arm 25 is operatively connected by 95 means of a link 26 to the sliding member 12, which carries a pawl 27 to engage with a ratchet 28 fast to a platen-axle 29. By means
of a finger-piece, not shown, the slide 12 is moved rearwardly when the carriage is re- 100

turned, thereby line-spacing both the tally-strip and the work-sheet.

In order to facilitate refilling the supply-spool 14, there is provided a key-hole-slot 30 in end brackets 31, so that a shaft 32, upon which the supply-spool is mounted, may be entered into the slots, and then rotated by means of a finger-piece 33 at the end of the shaft, thereby locking the spool in operating position. It will be noted that the receiving spool is rotatably mounted upon end plates 34 of a frame rockably mounted upon the shaft 22, on which it is swung upwardly to remove the supply-spool 14. Said spool 14 is prevented from rotating backwardly by means of a pawl 35 engaging with the cogs of the gear 20. The plates 34 may be tied together by means of tie-rods 36 and 37.

Referring to Figure 4, in which a novel work-sheet is illustrated, it will be noted that there is provided a narrow statement-sheet 38 forming an integral part of a record-sheet 39, which is provided with a pair of side extensions or feeding flaps 46 and 47, the two sheets being of substantially the same length and being attached at the top thereof by a weakened line 40. The two sheets are interleaved with a carbon 42, so as to form a pack, and the leading edge thereof is inserted at the rear of the platen, over a table 43 in back of the tally-strip, and is pushed down, so that its leading edge at the feeding flaps will be squared against the feed rolls. Then the platen is rotated by a finger-piece 44, and the work-sheet is positioned for the first line of typing, as shown in Figure 3.

Other lines of typing are spaced by means of the line-spacing mechanism in the regular manner, and the platen is always line-spaced as the carriage is returned previously to withdrawing the work-sheet from the machine, to permit the insertion of a fresh sheet.

Since it is desired to laterally position the work-sheet relatively to the position of the tally-strip, there may be provided a side gage 45, slidably mounted upon the rear table 43.

It will be noted that data may be typed directly on the record-sheet 39 at the sides of the statement-sheet 38 without having the data appear on the latter sheet or on the tally-strip.

Variations may be resorted to within the scope of the invention, and portions of the improvements may be used without others.

Having thus described my invention, I claim:

1. A work-pack for use in a typewriting machine over an independently-feedable tally-strip, said work pack including a form-printed bill-sheet adapted to be superposed upon a tally-strip and approximately corresponding therewith in width, a record-sheet folded under said bill-sheet and secured thereto by means of a friable connection between the upper edges of both sheets, and a

pair of integral feeding flaps upon said record-sheet extending to both sides in such manner as to materially widen the record-sheet, so that both said feeding flaps may be engaged by the end feed-rolls of the machine, whereby to feed said record-sheet and thereby feed said bill-sheet without contact of the feed-rolls with the latter sheet.

2. A work-pack for use in a typewriting machine over an independently-feedable tally-strip including a record-sheet which is adapted to be superposed on said tally-strip and relatively wider than the distance between the end feed-rolls of the machine and also adapted to extend over the tally-strip on both sides, and a front sheet overlying said record-sheet intermediately of the sides thereof and friably connected thereto at the top thereof, whereby to be feedable therewith, said front sheet being relatively narrower than the distance between said feed-rolls and corresponding approximately with the tally-strip in width.

ARTHUR A. BRADLEY.
